(57) **CLAIM**

The ornamental design for an identifier tag lens cover, as
shown and described.

DESCRIPTION

FIG. 1 is a top perspective view illustrating the new design;
FIG. 2 is a bottom perspective view thereof;

FIG. 3 is a top plan view thereof;

FIG. 4 is a first side elevational view thereof, the opposite
side elevational view being identical thereto;

FIG. 5 is a bottom plan view thereof;

FIG. 6 is a first end elevational view thereof, the opposite
end elevational view being identical thereto; and,

FIG. 7 is a bottom plan view of the second embodiment
thereof, wherein the only difference resides in the attaching
features.
